CLAIM

The ornamental design for a mobile apparatus for surface measurements, as shown and described.

DESCRIPTION

FIG. 1 shows a perspective view of an embodiment of the present invention.

FIG. 2 shows a front view of an embodiment of the present invention.

FIG. 3 shows a back view of an embodiment of the present invention.

FIG. 4 shows a bottom view of an embodiment of the present invention.

FIG. 5 shows a top view of an embodiment of the present invention.

FIG. 6 shows a side view of an embodiment of the present invention.

FIG. 7 shows a side view of an embodiment of the present invention; and,

FIG. 8 shows a perspective view of an embodiment of the present invention.

The broken line showing of elements is included for the purpose of illustrating non-claimed subject matter and forms no part of the claimed design.
